UNITED STATES PATENT OFFICE.

FRED W. LOEFFLER, OF IRONDEQUOIT, NEW YORK, ASSIGNOR TO THE BRYANT ELECTRIC COMPANY, OF BRIDGEPORT, CONNECTICUT, A CORPORATION OF CONNECTICUT.

ELECTRIC SWITCH.

1,387,419.

Specification of Letters Patent.

Patented Aug. 9, 1921.

Application filed January 3, 1917. Serial No. 140,479.

To all whom it may concern:

Be it known that I, FRED W. LOEFFLER, a citizen of the United States of America, and residing at Irondequoit, in the county 5 of Monroe and State of New York, have invented a certain new and Improved Electric Switch, of which the following is a specification.

My invention relates to electric switches 10 and particularly to flush switches such as are commonly employed for controlling lighting circuits, the object of my invention being to provide a compact switch device for independently controlling different groups 15 of lights from a single point.

In the accompanying drawings,

Figure 1 is a longitudinal section drawn to an enlarged scale, through a switch in which my invention is embodied in one 20 form;

Fig. 2 is a plan thereof; and

Fig. 3 is a perspective of a combined terminal used for connection to one of the main leads.

25 It is common practice in lighting installations, particularly for dwellings, to provide independent groups of lights in a single room or hall, or the like, and control these groups independently. Heretofore the

30 control has generally been effected through a single switch of such character that in order to change from one group to the other, it is necessary to pass through the intermediate group or groups successively. In other

35 words, it is impossible to obtain directly the lighting group which it is desired to utilize. Such switches have the advantage of compactness however, and are of such type that they can be mounted in a single gang switch

40 box, a feature of considerable value in domestic installations since the switch panel may be thereby made inconspicuous and neat. By the present invention I attain this

45 end and at the same time provide a switch installation of such nature that the lighting groups may be controlled absolutely independently of each other.

The construction which I employ for this purpose comprises a cup-shaped insulating 50 body 10 divided by a transverse partition 11 into two independent switch chambers 12 and 13. To these chambers one branch of the lighting circuit is led by a wire terminal 14 having two lugs 15 and 16 offset at 55 their lower ends to form switch terminals

17 and 18 on opposite sides of the barrier 11, the latter and the side wall of the insulating body being suitably recessed to this end. At the corners of the base and on the opposite side thereof, I arrange coöperating switch 60 terminals 19 and 20 in the respective switch chambers 12 and 13, and preferably also having the form of straps, the upper ends of which are offset to overlie depressed ledges and carry binding screws 21 and 22 for the 65 leads to the respective independent groups of lights.

Identical switch mechanisms are employed in the two switch chambers, and they are of such character and size that the entire 70 device is no larger than the ordinary switch body adapted to be mounted in a single gang switch box. Each mechanism comprises a switch blade 23 adapted to bridge the switch terminals 18 19, or 17—20 and carried by an 75 escapement plate 24 mounted freely on the switch spindle 25. This plate is subjected to the action of the switch spring 26, one end of which engages the lug 27 on the plate, while the other end is engaged by a 80 lug 28 on the crown plate 29 fast with the spindle 25. A coöperating crown plate 30 is carried at the foot of the spirally grooved cylindrical post 31 on which works the hollow push button 32 having spiral ribs 33 to 85 engage the spiral grooves 34 of the post. In as much as the push button is held against rotation by its guides 35 which engage the guide pins 36 carried by the frame member 37, the downward push of the but- 90 ton 32 serves to rotate the post 31 and thus not only tensions the spring 26 but also operates (through spindle 25) an escape- 95 ment mechanism 38 of well known type for releasing the plate 24 and thus permitting the blade 23 to move to its succeeding position.

In the position of the switch shown both blades 23 are in the "on" position and the lamps of both lighting groups A and B are 100 lighted. If the right hand button 32 is depressed the blade 23 is moved to "off" position, and the circuit through group B is broken. If it is wished to reestablish this group, it is not necessary as heretofore, to 105 go through the operations of first extinguishing all the lamps, then lighting group A and thereafter again lighting group B. But upon the depression of the right hand button the lighting of the group B is at 110

once reestablished. The same would be equally true of the lights in group A. Yet the switch has merely the appearance of an ordinary two button snap switch and occupies no more space and requires no elaborate wiring.

Various modifications in detail of construction will readily occur to those skilled in the art which do not depart from what I claim as my invention.

I claim as my invention:—

1. An electric switch comprising a cup-shaped insulating body, barrier means subdividing the interior thereof into separate switch chambers, independent switch mechanisms and switch terminals mounted in said switch chambers, wire terminals at the opposite ends of said body respectively connected to said independent switch terminals,
2. in combination with a wire terminal mounted on said body and comprising a strap having lugs offset into the respective switch chambers to coöperate with the switch mechanisms therein, substantially as described.
3. An electric switch device comprising a cup-shaped insulating body adapted to be

mounted in a single gang standard outlet box, independent switch mechanisms mounted within said cup-shaped body, means for operating said switches independently, and a pair of electrically connected switch terminals projecting in different directions into operative association with the respective switch mechanisms.

3. An electric switch device comprising a cup-shaped insulating body adapted to be mounted in a single gang standard outlet box, independent switch mechanisms mounted within said cup-shaped body, means for operating said switches independently, a wire terminal mounted on said body and a pair of switch terminals projecting from said wire terminal at an angle to each other into operative association with the respective switch mechanisms.

In testimony whereof I have signed my name to this specification, in the presence of two subscribing witnesses.

FRED W. LOEFFLER.
